CLAIM

The ornamental design for a numerical controller for processing machine, as shown and described.

DESCRIPTION

FIG. 1 is a perspective view thereof;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference perspective view in a state where a monitor is moved; and,

FIG. 9 is a reference right side view of usage.

The broken lines shown represent unclaimed subject matter of a numerical controller for processing machine and form no part of the claimed design.
